CLAIM

The ornamental design for a projector equipped with a lamp, as shown and described.

DESCRIPTION

FIG. 1 is a perspective view of a projector equipped with a lamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof in a state which the support, the projector and the lamp are moved;

FIG. 9 is a front view thereof in a state which the support, the projector and the lamp are moved;

FIG. 10 is a rear view thereof in a state which the support, the projector and the lamp are moved;

FIG. 11 is a left side view thereof in a state which the support, the projector and the lamp are moved;

FIG. 12 is a right side view thereof in a state which the support, the projector and the lamp are moved;

FIG. 13 is a top view thereof in a state which the support, the projector and the lamp are moved; and,

FIG. 14 is a bottom view thereof in a state which the support, the projector and the lamp are moved.

The dashed broken lines illustrate portions of the projector equipped with a lamp and form no part of the claimed design.

The support is gradually changed from a quadrilateral to a circular from the bottom end to the top end and from part of the claimed design.
